INVENTOR.

United States Patent Office.

THOMAS R. GOULD, OF BOSTON, MASSACHUSETTS.

Design No. 3,011, dated May 5, 1868.

DESIGN FOR A STATUETTE OF W. E. CHANNING.

The Schedule referred to in these Letters Patent and making part of the same.

TO ALL WHOM IT MAY CONCERN:

Be it known that I, THOMAS R. GOULD, of Boston, in the county of Suffolk, and State of Massachusetts, have originated and designed a Statuette of William E. Channing, of which the accompanying illustration is a faithful representation.

I have made but one view, as, from the nature of the case, a single faithful representation reveals the entire character of the work. The statuette may be made of any material whatever that is capable of being worked.

What I claim as my invention, and desire to secure by Letters Patent of the United States, is—
The design for a statuette, herein set forth and shown.

THOMAS R. GOULD.
